by Amy North Janey Tamm
Harris.

UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

SINKER OR WEB-HOLDER CAM MECHANISM FOR KNITTING MACHINES.

Original application filed October 1, 1920, Serial No. 414,085. Divided and this application filed March 30, 1922. Serial No. 548,160.

To all whom it may concern:

Be it known that I, GEORGE P. BOSWORTH, a citizen of the United States, and a resident of Central Falls, in the county of Providence and State of Rhode Island, have invented an Improvement in Sinker or Web-Holder Cam Mechanism for Knitting Machines, of which the following description, in connection with the accompanying drawings, is a specification, like characters on the drawing representing like parts.

This application is a division of my pending application Serial No. 414,085, filed October 1, 1920.

This invention relates to knitting machines and particularly to instruments for operating web holders, sinkers or like instrumentalities. The invention will be best understood by reference to the following description when taken in connection with the accompanying drawing, wherein—

Fig. 1 is a plan view of a so-called sinker ring upon which the various cams for operating the sinkers or web holders are supported;

Fig. 2 is a vertical section upon the line 2—2 of Fig. 1; and

Fig. 3 is a side elevation of the inner member of the cap ring of Fig. 1.

The present invention is applicable to various types of machines, but the present embodiment thereof involves a circular knitting machine having the principal characteristics of the so-called Banner machine disclosed in the Hemphill Patent No. 933,443, patented September 7, 1909.

Furthermore the invention is capable of use with both spring beard and latch needle machines. In the type of knitting machine disclosed the needle carrier is of cylindrical form and contains a circular series of independently movable needles, the needle cylinder and cap ring having relatively rotary movement so as to effect the operation of the reciprocating elements, herein web holders or sinkers. I have not illustrated the needle cylinder, but it is provided with a series of needles adapted to be reciprocated therein in the usual manner. Attached to said cylinder is a sinker or web holder bed ring, and having usual grooves radially positioned with relation to the center of the needle cylinder to receive the web holders or

sinkers. The needles, which may be latch needles or spring beard needles, are raised or lowered in the usual loop forming manner by appropriate knitting cams, not herein shown. In some machines the reciprocating elements above referred to are employed to sink the yarn between the stems of the needles when in their elevated positions, while in other machines similar elements may be used for holding the web during the raising of the needles to prevent such web from being elevated therewith, particularly when no tension is applied to the knitted fabric. When such elements are used, means are required to impart the necessary reciprocating movements thereto in order to effect the cooperation of said elements with the needles, and whether sinkers or web holders are employed, similar reciprocating means are necessary. In the present embodiment of the invention, the reciprocating elements are in the form of web holders, to which, however, the invention is in no wise restricted, and the term "web holder" is used in a general sense. Said web holders may be of any suitable design for engaging the work and holding the same during the raising of the needles in order to prevent said work from being carried upwardly thereby. Such web holders as is customary are provided with operating butts projecting upwardly from the upper edge of the web holders.

In order to reciprocate said elements (herein web holders) the present embodiment of the invention involves the use of a cap ring comprising an outer member 1 and an inner member 2, the latter being arranged concentric with the outer member and engaging said outer member along an annular line, both of said members being in the form of rings, as is clearly evident from Figs. 1 and 2. The said inner and outer members are so formed upon their under surfaces as to provide an annular groove indicated in part at 3 in Fig. 2, wherein the butts of the web holders are received, so that said butts may engage and be controlled by the opposed faces of said members 1 and 2.

The under faces of the said annular members lie substantially in the same plane, as indicated in Fig. 2, and are adapted to engage the upper edges of the web holders

and rest upon the corresponding upper face of the web holder bed ring shown at 3', thus providing suitable supporting and guiding means for said ring. The outer margin 5 of the ring 1 is extended below the upper edge of the web holder bed ring and constitutes a guide for said cap ring, thus properly positioning the latter upon said bed ring. In knitting machines with which the 10 present mechanism is to be used, the needle carrier and cams reciprocating the needles in the grooves of the carrier, are capable of relative rotary and reciprocating movements, and the mechanisms for effecting 15 these movements are very well known to those skilled in the art. Therefore, no illustration or description thereof is necessary.

During the reciprocating movements of 20 the knitting machine, it is desirable to effect a relative movement between the cap ring and the reciprocating elements (herein web holders), and in the present embodiment of the invention means are provided consisting 25 of the two armed brackets 5 attached to the said cap ring by screws 6-6. The arms 7-7 of said bracket extend in substantially radial directions from the ring and support adjacent their outer ends adjustable stop 30 screws 8-8. The screws 8 are arranged so as automatically to engage a standard 9 carried by said same part of the knitting machine frame, and herein the standard 35 constitutes the support for the latch ring or yarn guide supporting member and is carried by a part which does not move with the needle cylinder, thereby creating a relative movement between said cap ring and said needle cylinder. The positions of the screws 40 8, 8 may be such as to permit a slight shogging movement of the ring to take place during the reciprocations of the needle cylinder, but, as indicated, such movement may be very small and practically negligible.

When relative reciprocating movements are desired between the needle cylinder and the cap ring, as in the formation of flat webs or heel and toe pockets, two sets of 50 cams are usually employed for operating the web holders at the proper intervals to cooperate with the needle in the loop forming operations. Hence in the disclosed embodiment of the invention two such sets of cams 55 are provided, each set including a web holder advancing cam, and a web holder retracting cam being in the disclosed embodiment of the invention formed as a single piece and having parts or formations cooperating 60 with each advancing cam.

During the operation of the machine, the inner and outer ring members 1, 2 are caused to cooperate in their action by appropriate stops consisting of brackets 10, 10 secured 65 to one of the ring members and herein the

outer ring member 1 and bearing adjusting screws 11, 11 arranged in opposed relation to engage opposite portions of an abutment 12 secured to one ring member, herein the inner member 2. Obviously the brackets 70 10 may be positioned at predetermined distances apart, so as to cause the screws 11 to engage said abutment 12 when desired.

In the disclosed embodiment of the invention, both sets of cams, including the advancing and retracting cams, are mounted upon the inner ring member 2. The web holder retracting cam, as shown at 13, is made in one piece, which piece is inserted in a suitable gap or recess milled part way through the inner ring member 2. The said cam is adjustably mounted by screws 14, 14 positioned adjacent opposite ends of said cam 13 and permitting either end of said cam to be moved without substantial movement of the other, because of the radial slots 14' receiving said screws.

The advancing cams are indicated at 15, 15 and are represented as pivotally attached by screws 16, 16 to the under side of plates 17, 17, which are themselves secured to the upper face of the inner ring member 2 by screws 18, 18, so that by loosening up on the screws 16 the said cam 15 may be swung in or out to vary the position of the said cams relatively to the cam ends of the cam member 13.

When the invention is employed with spring beard needle machines, presser cams 100 may be employed, as indicated at 19, 19, 19 in Fig. 1 to operate upon desirably individual pressers.

It will be observed, viewing Fig. 1, that the outer ring member is provided upon its inner face with an arc shaped recess 20, wherein are received the cams of the inner ring member 2, said recess being of sufficient length to permit the relative movement of said ring members 1 and 2.

By supporting all of the said cams upon one of the ring members, said cams are rendered more readily accessible, and it is obvious that in the reciprocating movements in knitting flat webs or in the production of heel and toe work, it is necessary to reciprocate merely the ring which directly carries the said cams.

Having thus described one illustrative embodiment of my invention, I desire it to be understood that although specific terms are employed, they are used in a generic and descriptive sense and not for purposes of limitation, the scope of the invention being set forth in the following claims.

1. In circular knitting mechanism employing a circular series of sinkers, web holders or like instrumentalities, and a bed ring receiving the same, a cap ring for said instrumentalities adapted to overlie said instrumentalities and bed ring and including rela-

- tively movable inner and outer curved members together providing a groove for the reception of the entire series of instrumentalities, advancing and retracting cams carried wholly by one of said members, means to permit predetermined relative movement between said inner and outer members, and means to permit a predetermined shogging movement of said ring.
- 10 2. In circular knitting mechanism employing a circular series of sinkers, web holders or like instrumentalities, and a bed ring receiving the same, a cap ring for said instrumentalities adapted to overlie said instrumentalities and bed ring and including relatively movable inner and outer curved members together providing a groove for the reception of the entire series of instrumentalities, advancing and retracting cams carried wholly by one of said members, and means to permit predetermined relative movement between said inner and outer members.
- 15 3. In circular knitting mechanism employing a circular series of sinkers, web holders or like instrumentalities, and a bed ring receiving the same, a cap ring for said instrumentalities adapted to overlie said instrumentalities and bed ring and including relatively movable inner and outer curved members together providing a groove for the reception of the entire series of instrumentalities, advancing and retracting cams carried wholly by said inner member, means to permit predetermined relative movement between said inner and outer members, and means to permit a predetermined shogging movement of said ring.
- 20 4. In circular knitting mechanism employing a circular series of sinkers, web holders or like instrumentalities, and a bed ring receiving the same, a cap ring for said instrumentalities adapted to overlie said instrumentalities and bed ring and including relatively movable inner and outer concentric rings which together provide a groove for the reception of the entire series of instrumentalities, advancing and retracting cams wholly carried by said inner ring, means to permit predetermined relative movement between said inner and outer concentric rings, and means to permit a predetermined shogging movement of said cap ring.
- 25 5. In circular knitting mechanism employing a circular series of sinkers, web holders or like instrumentalities, and a bed ring receiving the same, a cap ring for said instrumentalities adapted to overlie said instrumentalities and bed ring and including relatively movable inner and outer curved members together providing a groove for the reception of the entire series of instrumentalities, advancing and retracting cams carried wholly by said inner member, said cams being adjustably mounted relative to each other, and means to permit relative circular movement between said curved members.
- 30 6. In circular knitting mechanism employing a circular series of sinkers, web holders or like instrumentalities and a bed ring receiving the same, cams to reciprocate said instrumentalities, a cam carrier adapted to overlie said instrumentalities and bed ring and including inner and outer members arranged for relative or synchronous movement, said members together providing a groove for the reception of the entire series of instrumentalities, said cams being secured wholly to said inner member, and means on said outer member to effect relative movement between said reciprocating elements and said cam carrier.
- 35 7. In knitting mechanism employing sinkers, web holders or like instrumentalities, and a bed ring receiving the same, a cap ring for said instrumentalities adapted to overlie said instrumentalities and bed ring and including inner and outer concentric rings 1, 2, the outer ring having an arc shaped recess 20, a single retracting cam 13 and two advancing cams 15 at opposite sides thereof, all of said cams being secured to the inner ring member and projecting into said recess 20.
- 40 8. In circular knitting mechanism employing a circular series of sinkers, web holders or like instrumentalities, and a bed ring receiving the same, a cap ring for said instrumentalities adapted to overlie said instrumentalities and bed ring and including relatively movable inner and outer curved members together providing a groove for the reception of the entire series of instrumentalities, a pair of advancing cams 15 having pivots, plates 17 secured to the inner curved member and to which said advancing cams 15 are pivoted with capacity for adjustment and retracting cam means between said advancing cams.
- 45 9. In circular knitting mechanism employing a circular series of sinkers, web holders or like instrumentalities, and a bed ring receiving the same, a cap ring for said instrumentalities adapted to overlie said instrumentalities and bed ring and including relatively movable inner and outer curved members together providing a groove for the reception of the entire series of instrumentalities, a pair of advancing cams carried by the inner curved member, and an intermediate retracting cam 13, and means at each end of said retracting cam consisting of radial slots and screw like projections therein for permitting adjustment of said retracting cam.
- 50 10. In circular knitting mechanism employing a circular series of sinkers, web holders or like instrumentalities, and a bed ring receiving the same, a cap ring for said instrumentalities adapted to overlie said instrumentalities and bed ring and including

relatively movable inner and outer ring like members together providing a groove for the reception of the entire series of instrumentalities, the said outer ring like member 5 having an arc shaped recess 20, and the inner ring like member having advancing and retracting cams carried thereby and received

in said arc shaped recess, the latter being sufficiently prolonged to permit relative movement of the parts of said cap ring. 10

In testimony whereof, I have signed my name to this specification.

GEORGE P. BOSWORTH.
